UNITED STATES PATENT OFFICE.

WALTER A. RARIG, OF OAKLAND, CALIFORNIA.

DESIGN FOR A SIGHT-FEED FOR OIL-PIPE.

54,862.

Specification for Design.

Patented Apr. 13, 1920.

Application filed June 30, 1919. Serial No. 307,868. Term of patent 7 years.

To all whom it may concern:

Be it known that I, WALTER A. RARIG, a citizen of the United States, residing at Oakland, in the county of Alameda and State of California, have invented a new, original, and ornamental Design for a Sight-Feed for Oil-Pipe, of which the following is a specification.

Referring to the drawing, forming a part thereof:

Figure 1 is a side elevation of my design. Fig. 2 is a top plan view of my design.

I claim:

The ornamental design for a sight feed for oil-pipe, as shown.

In testimony whereof I affix my signature.

WALTER A. RARIG.
